(57) **CLAIM**

The ornamental design for a hood intake bezel, as shown and described.

DESCRIPTION

FIG. 1 is a top isometric view of a hood intake bezel according to our new design;

FIG. 2 is a bottom isometric view of a hood intake bezel of FIG. 1;

FIG. 3 is a front view of the hood intake bezel of FIG. 1;

FIG. 4 is a top view of the hood intake bezel of FIG. 1;

FIG. 5 is a bottom view of the hood intake bezel of FIG. 1;

FIG. 6 is a left side view of the hood intake bezel of FIG. 1;

FIG. 7 is a right side view of the hood intake bezel of FIG. 1;

FIG. 8 is a partial cross-sectional view taken along line 8-8 in FIG. 3; and,

FIG. 9 is a partial cross-section view taken along line 9-9 in FIG. 3.

The broken lines show portions of the hood intake bezel which form no part of the claimed design.

FIGS. 1-9 illustrate a first embodiment of our novel design suitable for use on one side of a vehicle. Our novel design also includes a second embodiment suitable for use on the opposite side of a vehicle, which is mirror symmetrical to FIGS. 1-9 and therefore not separately illustrated.
